MIXER

Edward A. Brown, Dodge City, Kans.

Application November 25, 1941, Serial No. 420,385

14 Claims. (Cl. 259—54)

This invention relates generally to new and useful improvements in mixing apparatus and has particular reference to improvements in mixing apparatus for bottled goods, such as, for example, bottled beverages and other bottled liquids.

The invention is particularly adapted to apparatus for mixing of bottled non-alcoholic beverages composed of carbonated water and syrup. Bottling plants making such beverages employ filling machines whereby the bottles are successively filled with a flavored syrup and carbonated water. In such filling operations, the carbonated water is disposed above the syrup which is within the bottom portion of the bottle. Obviously, the syrup and carbonated water must be mixed before such bottled beverages are shipped from the bottling plant and this invention is directed to comparatively simple and novel apparatus for mixing such bottled beverages.

An object of my invention is to provide mixing apparatus including means for successively feeding a plurality of cases of bottled goods into an intermittently rotatable drum and simultaneously during the successive circular movements of the cases with the drum bodily rotating each case of bottled goods to thereby mix the contents of the bottles in the cases.

Another object of my invention is found in the provision of mixing apparatus including an intermittently rotatable device carrying a plurality of circularly spaced receptacles each supporting a case of bottled goods and including a continuously operating power-driven mechanism, means for automatically feeding and discharging the cases into and from the device, and mechanism for automatically periodically stopping the rotation of the device during the reception and discharge of the cases by and from the device during the uninterrupted operation of the power-driven mechanism.

In the attached drawings:

Fig. 1 illustrates a plan view of mixing apparatus, for bottled goods, embodying a preferred form of my invention;

Fig. 2 is a vertical section of the mixing portion of the apparatus taken on line 2—2 of Fig. 1; the feeder being also shown in side elevation;

Fig. 3 is a vertical section similar to Fig. 2 but taken on line 3—3 of Fig. 1;

Fig. 4 is a vertical section taken on line 4—4 of Fig. 3; and

Fig. 5 is a side elevation of the entire apparatus on a slightly reduced scale.

In the illustrations showing a preferred embodiment of my invention, the mixing apparatus comprises a metallic framed structure including upper side angle irons 10, bottom angle irons 11, vertical angle iron posts 12, and top transverse or end angle irons 13.

10 A suitable platform 14, preferably of wood, is supported on the above-described framed structure and is adapted to support the electric motor 15 which drives a suitable mechanical speed reducer 16 through the medium of a drive belt 17 trained about the motor pulley 18 and the speed reducer drive pulley 19.

15 The output shaft 20 of the speed reducer 16 carries, at its outer extension, a cam 21, another cam 22, and the segmental drive gear 23.

20 The mixing apparatus includes a rotatable device or drum 25 composed of a pair of circular disk-like end members 26 secured together in relatively spaced positions by the circularly spaced transverse bolts 27 which pass through the pipe separators 28.

25 The drum disk-like end members 26 are rotatably supported on a central shaft 29 extending through flanged hubs 31 bolted to the members 26, and the stationary shaft 29 is supported in bearings 30 on the upper side angle irons 10.

30 The drum 25 is adapted to be intermittently rotated by the driven gear 24 which is suitably secured to one of the members 26 and the gear 24 is adapted to mesh with a driving segmental gear 23. The ratio of the number of gear teeth on the segment 23 to the number of gear teeth on the driven gear 24 is such that the drum 25 makes one-fourth of a revolution during the operative engagement of the segmental gear 23 with the gear 24 in each revolution of the drive shaft 20.

35 The drum 25, as here illustrated, is provided with four receptacles 32 each rotatably supported at opposite end walls 36 on a pair of pins 33 fixed to such opposite end walls and rotatably positioned in the drum end members 26.

On one side of the rotatable device 25, the four pins 33 are each extended beyond the outer face of the end member 26 into operative engagement with a gear 34 and the four similar gears 34 are in mesh with a similar gear 35 which is fixed to the stationary drum shaft 29 and therefore this central or sun gear 35 is at all times stationary while the planetary gears 34 are adapted to rotate during the intermittent rotation of the drum 25 through the gear 24 fixed thereto and the segmental gear 23 which is rotated, or more

specifically speaking revolved, by the motor-driven drive shaft 20.

As above stated, the drum 25 makes only one-fourth of a revolution during each complete revolution of the drive shaft 20, but through the above described sun and planetary gear arrangement, shown particularly in Figs. 2, 3 and 5, each receptacle 32 will, during such quarter revolution of the drum 25, make a one-half revolution relatively to a horizontal line.

Since all four receptacles 32 are alike, a description of one will suffice.

Each receptacle 32 consists of the end walls 36, a top wall 37, a bottom wall 38, and rear side wall 39. The front side of the receptacle is open to receive therein a case 40 of the bottled goods as shown more clearly in Fig. 3.

Each receptacle 32 is provided with a gate 41 which extends, when in closed position, across the open side of the receptacle to prevent displacement of the case 40 therefrom. This gate 41 has short integral side wings 42 which, in closed position, extend over the outer face of the end walls 36, and the gate 41 is pivoted to the bottom wall 38 as at 43.

Each gate 41 is also provided with a pair of slightly offset side arms 44 which are formed integrally with the gate side wings 42 and each arm 44 carries a roller 45 at the terminus thereof.

Each receptacle 32 is also provided with a pair of bars 46 each secured to an end wall 36 but depending below the bottom wall 38 for securement thereto of one end of springs 47 whose opposite ends are secured to the side wings 42. The mounting of these springs 47 with reference to the pivot 43 being such that these springs will retain the closure gate 41 in either closed or open position. As more clearly shown in Fig. 3, the gate plate 41 extends slightly beyond the hinge 43 and this extended portion of the gate plate functions as a stop or abutment to retain the gate 41 in open position during loading of the case 40 into the receptacle and also during the discharge of the case 40 from the receptacle.

Each gate plate 41 is also provided with a comparative thick plate 41^A secured to the inner face of the gate plate 41 the exposed face of which is adapted to form a bridge support aligned with the upper face of the horizontal legs of the angle irons 49. This plate 41^A also engages the side of the case 40, when the gate 41 is closed, to retain the case 40 against shifting while the two comparatively heavy springs 47 retain the gate in closed position.

My invention also includes automatically operable means for feeding the cases 40, one by one, into the drum 25 during the intermission between each quarter revolution of the drum.

The feeding means, as herein illustrated, consists of an elongated table 48 composed of a pair of spaced horizontal angle irons 49 adapted to support a plurality of longitudinally aligned cases 40 of the bottled goods.

The case-supporting angle irons 49 are supported at the case-discharge end on the transversely disposed angle iron 13 and at the case-inlet end on a pair of suitable vertical supports 50.

The feeding means includes a pusher consisting of a pair of longitudinal flat bars 51 each slidably supported on the upper edge of the vertical leg of the angle iron 49 by means of a transversely disposed bent plate member 53 extending across the table 48, under the horizontal legs of the two angle irons 49 and thence upwardly on

the outer sides of the vertical legs of the angle irons 49 and terminating in hooked ends slidably embracing the vertical legs of the angle irons 49.

5 To provide a support for means for adjusting the pusher, I prefer to provide the pusher with another bent plate member 53 spaced rearwardly from the first-mentioned bar member 53. The plate members 53 are connected together at their 10 transverse portions by a pair of spaced longitudinal plates 54 so that the pusher parts are slidable as a unit on the angle irons 49.

At the casing-engaging end of the pusher, both of the bars 51 are bent upwardly, as at 51^A, to support the hinged case-engaging members 55. The members 55 are vertical plate members each provided with a hinge supported on the upstanding portion 51^A so that each case-engaging member 55 is normally held in position for engagement of the case 40 to push it into one of the aligned receptacles 32.

If, during the forward feeding movement of the slidable pusher, another case 40 is manually moved on the table into the feeding position previously occupied by the case then being fed into the drum mixer, the case-engaging members 55 will then, in their rearward return movement and engagement with the case 40 about to be loaded into the mixer, swing outwardly against the pressure of their springs and after the case-engaging members 55 have passed the rear end of the case 40, the springs will move the members 55 into the proper case-engaging position whereupon the pusher is then ready to push such next case 40 into the drum mixer.

35 The feeding means also includes an operating mechanism for reciprocating the case-pusher which comprises a reciprocable gear rack 56 slidably mounted in a channeled portion 57^A of an elongated inclined bar member 57 pivotally supported, at its lower end, on pin 58 carried on the structural frame. The rack-supporting member 57 is freely supported, at its upper end, on a coil spring 59 mounted on a bent plate 60 secured to one of the upright supports 12.

40 The upper end of the rack 56 is pivotally connected to one end of the pusher operating rod 61 having a threaded connection with a head 62 which is pivotally connected, at 63, with the lower end of the adjustable connector 64. The connector 64 is slidably supported on the horizontal bar 65 which is riveted to the two plate members 53. The pusher is slidably adjustable relatively to the connector 64 for proper movement to properly feed the cases 40 into the drum receptacles 32 and, when so adjusted, the connector 64 is securely connected to the pusher bar 65 as by means of a set-screw 66 so that the pusher is movable with the reciprocating operating rod 61 of the reciprocating rack 56.

45 The rack 56 is held in operative position for engagement by the segmental gear 23 by the coil spring 59 when the segmental gear 23 is disengaged from the drum-rotating gear 24 and while the drum 25 is in stationary position to permit loading of the cases 40 therein.

50 The rack-supporting member 57 is provided with an upstanding bracket 67 rigidly secured to the outer side of the member 57 and provided with a roller 68 thereon arranged for operative engagement by the cam 22 which is rotatable with the drive shaft 20.

55 As shown in Figs. 1, 2 and 3, the mixer is shown in the position just preceding the loading of the case 40, shown on the table, and just after one of

the cases 40 has been automatically discharged from the drum 25 onto the inclined chute 69 from the receptacle 32 now aligned with the case-discharge end of the feeding means. The relative positions of the parts and members at this stage of operation is more clearly shown in Fig. 2 wherein the drum-operating segmental gear 23 is about to pass from its engagement with the drum gear 24 into engagement with the rack 56.

As shown in Fig. 2, the larger portion of the cam 22 is shown in engagement with the roller 68 and this larger portion of the cam 22 is still retaining the member 57 and rack 56 in depressed position, against the pressure of the coil spring 59, whereby the rack 56 is held out of operative engagement with the segmental gear 23, however, when the segmental gear 23 becomes only slightly more advanced in its rotation from the position shown in Fig. 2, the smaller portion of the cam 22 will permit the spring 59 to slightly raise the member 57 so that the rack 56 will be engageable by the segmental gear 23 to thus shift the rack 56 downwardly within the channeled portion 57A and thereby pull the rod 61 and pusher into feeding position.

Simultaneously with the feeding operation just described, the cam 21 will release the movement of the roller 70 which is rotatably supported on the lower end of the operating rod 71 of the drum-locking-mechanism to thereby lock the drum against any possible rotation while the case 40 is being fed therein.

The drum-locking-mechanism, as shown more clearly in Figs. 1, 2, 3 and 5, consists of a shaft 72 oscillatably supported in the side angle irons 10 and oscillatably connected to the operating rod 71 by means of a collar 73 fixed to the shaft 72 and pivotally connected with the upper end of the rod 71.

Fixed to the shaft 72 is a hook-like dog 74. When the mixing device is in the position shown in Figs. 1, 2 and 5, the large portion of the cam 21 retains the operating rod 71 in the upwardly shifted position wherein the locking dog 74 is held in raised unlocked position. The operating rod 71 is slidably supported in a sleeve 75 pivotally mounted on a depending bar 76 and a coil spring 77 interposed between the supporting head for the roller 70 and the sleeve 75 functions to retain the roller 70 in continuous operative engagement with the cam 21.

It will be observed from Fig. 2 that the cams 21 and 22 and their operatively associated mechanisms are so synchronized in operation that the greater cam portions are practically simultaneously disengaged from the rollers 68 and 70 so that the locking dog 74 is moved into locking engagement between the teeth of one of the planetary gears 34 to thereby prevent rotation of the drum 25 just before the rack 56 is permitted to move into operative feeding engagement with the segmental gear 23, and these cams 21 and 22 also function to disengage the dog 74 from locking engagement with one of the gears 34 just prior to the engagement of the segmental gear 23 with the drum-rotating gear 24.

When the segmental gear 23 has moved the rack 56 and the case pusher into the final loading position with the case 40 within the receptacle 32, and when the last tooth of the segmental gear 23 has become disengaged from the rack 56 and its associated case pusher will be automatically quickly retracted, to the position shown in Fig. 2, ready for their next loading operation. This automatic retraction of the rack and pusher is

attained through the employment of a coil spring 78 which is connected at one end to the case pusher rearmost plate member 53 and at its opposite end to a transverse angle iron 79.

To prevent reverse rotation of the drum 25 during the loading of the cases 40 therein, I mount on the peripheral face of one of the circular drum end members 26, four equal spaced elongated ratchet-like stops 80 each consisting of an elongated ratchet tooth adjustably mounted on a threaded rod 81 having ends supported in a pair of clip angles 82 secured to the peripheral face of the drum end member 26. The elongated ratchet stops 80 are adapted to be successively engaged, during the rotation of the drum 25, by a resilient dog 83 which is loosely supported on the shaft 72 but adjustably held in proper position by a rod 84 between a pair of adjustable nuts 85. The rod 84 is secured to a plate 86 by a pair of adjustable nuts 87. The free resilient end of the dog 83 is adapted to engage against the tooth 80A to prevent any possible reverse rotation of the mixing drum 25.

In the event it is desired to manually feed the cases 40 into the mixer and not to employ the automatic case-feeding means, the case-pusher mechanism may be manually disengaged from operation by the cam 22 and segmental gear 23 by moving the handle of the pivoted feed-disengaging lever 52 upwardly to the position shown by the broken lines in Fig. 2 thereby pushing the rack-carrying member 57 downwardly against the pressure of the spring 59 to thus render the rack 56 inoperative by the segmental gear 23.

My invention also includes means for automatically closing the gate 41 of each receptacle 32 after such mixer receptacle 32 is loaded with a case of the bottled goods. Separate means are provided for automatically opening the gate 41 of each receptacle 32 to permit the discharge of the case 40 therefrom prior to the positioning of the empty receptacle 32 at the point of loading. After the gate 41 of the receptacle 32 is opened to discharge the case 40 therefrom, such gate 41 remains open during the movement of the drum 25 to stationary loading position, but the gate 41 is gradually automatically closed, after such receptacle 32 is loaded, during the movement of the drum 25 in its next quarter rotation. During the first quarter rotation of the drum 25 with the case 40, which has been loaded into the drum 25 just prior to such quarter rotation, the gate 41 of the receptacle positioned at the lower part of the drum will, as it approaches the discharge chute 69, gradually be opened to discharge the case of the mixed goods into the discharge chute 69.

The above-described automatic closing and opening operations of the receptacle gates 41 are attained through the provision of a gate-closing cam 88 and a gate-opening cam 89 operatively associated with each receptacle 32. As shown more clearly in Figs. 1 and 3, these cams 88 and 89 are rigidly secured to the two circular drum ends 26 in relatively stationary positions and each pair of cams 88 and 89 is held in a fixed position relatively to the center-line of the pivotal pins 33 of its cooperating receptacle 32.

As shown in Fig. 1, all of the gate-closing cams 88 are mounted on one of the circular drum ends 26 and all of the gate-opening cams 89 are mounted on the other of the circular drum ends 26, and therefore, in the first operation of opening a receptacle gate 41 to discharge a case 40 onto the chute 69, one of the rollers 45 will en-

gage the inner face of its operatively associated gate-opening cam 89 as the receptacle 32 nears the end of its cycle of one complete rotation about the pins 33, to thus forcibly open the gate 41 to permit the case 40 to be discharged by gravity over the gate 41 when such gate 41 becomes aligned with the chute 69. As viewed in Fig. 3 the lowermost receptacle 32 has completed three-fourths of its complete cycle of rotation about its pivotal pins 33 and is shown in a position prior to the engagement of its roller 45 with the gate-opening cam 89 shown near the left side of the receptacle 32. The cases 40 are discharged from their receptacles 32 as the receptacles move upwardly from their lowermost position and prior to their stop at their loading position.

As viewed in Fig. 3, the right-hand receptacle 32, shown in cross-section, has reached the loading position and has just received another case 40 which has been pushed therein by the operation of the case pusher heretofore described.

When the segmental gear 23 is released from its pulling contact with the rack 56, the spring 78 will retract the pusher to the position shown in Fig. 2 and the segmental gear 23 will thereafter engage the drum-rotating gear 24 to rotate the mixing drum another quarter of one revolution, but in such quarter revolution, the gate 41 of the loaded receptacle 32 will be closed by the engagement of the other roller 45 thereof with its cooperating closing cam 88.

Various modifications and changes in the construction and arrangement of the various parts and members herein shown for illustrative purposes will become readily apparent to those skilled in the art to which this invention appertains, upon perusal of the above specifications and attached drawings, without departing from the spirit of my invention which is defined in the appended claims. I do not therefore wish to be understood as limiting myself to the exact details of construction and arrangement shown therein for purposes of illustrating one embodiment of my invention.

I claim:

1. Mixing apparatus comprising a stationary structure, an intermittently rotatable structure supported on said stationary structure, a plurality of intermittently rotatable receptacles carried by said rotatable structure and each adapted to support a container for the material to be mixed, means for rotating said receptacles during the rotation of said rotatable structure, a gate for each receptacle adapted to retain the container therein during the mixing operation, means for automatically successively opening the gates to permit the discharge of the containers from the receptacles, means for automatically successively closing the gates after each receptacle is charged with a container containing the material to be mixed, a motor, and mechanism driven by said motor for intermittently rotating said rotatable structure during the uninterrupted operation of said motor.

2. Mixing apparatus comprising a stationary structure, an intermittently rotatable structure supported on said stationary structure, said rotatable structure being rotatable about a horizontal axis, a plurality of intermittently rotatable supports carried by said rotatable structure and each adapted to support a container for the material to be mixed, means for rotating said supports during the rotation of said rotatable structure, movable means pivotally mounted on each of said supports for retaining said con-

tainers on said supports during the mixing of the material, automatically operable means for successively actuating said movable pivotally mounted means to permit the discharge of the containers from said supports, means for automatically successively actuating said movable pivotally mounted means to thereby move same into container-retaining position after each support is charged with a container of material to be mixed, a motor, and mechanism driven by said motor for intermittently rotating said rotatable structure during the uninterrupted operation of said motor.

3. Mixing apparatus as embodied in claim 2, wherein said motor-driven mechanism includes an intermittently driven gear operatively connected to said rotatable structure and a segmental driving gear, driven by said motor, adapted to intermittently mesh with said driven gear to thereby intermittently rotate said rotatable structure, and including means operable by said segmental driving gear for automatically loading the empty support with a container, with the material to be mixed, while said rotatable structure is in stationary position.

4. Mixing apparatus as embodied in claim 2 wherein said means for rotating said receptacles comprises a stationary gear supported on said stationary structure, and a planetary gear for each of said receptacles, said planetary gears being in mesh with said stationary gear and rotatable with said receptacles.

5. Mixing apparatus as embodied in claim 1 wherein said motor-driven mechanism includes an intermittently driven gear operatively connected to said rotatable structure and a segmental driving gear being adapted to intermittently mesh with said driven gear to thereby intermittently rotate said rotatable structure, and including means intermittently operable by said segmental driving gear for automatically loading the empty receptacle with a container, containing the material to be mixed, while said rotatable structure is in stationary position.

6. Mixing apparatus as embodied in claim 1 and including said means for automatically successively opening the gates to discharge the containers from said receptacles being operable during the latter portion of the cycle of rotation of each receptacle.

7. Mixing apparatus as embodied in claim 1 and including means for automatically loading the empty receptacle with a container, containing the material to be mixed while the rotatable structure is in stationary position, and a cam rotatable by said motor, automatically operable retaining means actuated by said cam for retaining said rotatable structure against rotation in forward or reverse direction during the loading of the empty receptacle.

8. Mixing apparatus comprising a stationary structure; an intermittently rotatable structure supported on said stationary structure; a plurality of intermittently rotatable receptacles carried on said rotatable structure and adapted to support the material to be mixed; means for rotating said receptacles during the rotation of said rotatable structure; a motor; mechanism driven by said motor for intermittently rotating said rotatable structure during the uninterrupted operation of said motor, said mechanism including an intermittently driven gear operatively connected to said rotatable structure, a segmental driving gear driven by said motor and adapted to intermittently mesh with said driven gear to

thereby intermittently rotate said rotatable structure; means for automatically periodically successively discharging the mixed material from said receptacles; and means operable by said segmental driving gear for automatically loading the empty receptacle with material to be mixed while said rotatable structure is in stationary position.

9. Mixing apparatus as embodied in claim 8 and including a cam-operable mechanism in synchronized operation with said segmental gear for automatically operating means for retaining said rotatable structure against rotation in forward or reverse direction during the loading of the empty receptacle.

10. Mixing apparatus comprising a stationary structure; an intermittently rotatable instrumentality rotatably supported on said stationary structure; an intermittently rotatable support carried on said rotatable instrumentality and adapted to support a container containing the material to be mixed; means for rotating said support during the rotation of said rotatable instrumentality; a pivoted retaining member on said support for retaining said container thereon during the mixing of the material therein; a motor; mechanism driven by said motor for intermittently rotating said instrumentality during the uninterrupted operation of said motor, said mechanism including an intermittently driven gear operatively connected to said instrumentality, a segmental driving gear driven by said motor and adapted to intermittently mesh with said driven gear to thereby intermittently rotate said instrumentality; means for automatically actuating said pivoted member to permit the discharge of the container with the mixed material from said support; and means operable by said segmental gear for automatically loading the empty support with another container of material while said instrumentality is in stationary position.

11. Beverage mixing apparatus comprising a stationary frame, a rotatable structure mounted on said frame, a plurality of rotatable receptacles carried on said rotatable structure each adapted to carry a case of bottled beverage, means for simultaneously rotating said receptacles during the rotation of said rotatable structure, a gate for each receptacle, releasable means for retaining each of said gates in closed position to retain the case therein, a pair of arms projecting from each gate, gate-opening and gate closing cam means for each receptacle, said cam means being mounted on said rotatable structure and adapted to be alternately engaged by said arms of each gate to thereby open the receptacle gate to permit the discharge of the case of bottled beverage from the receptacle prior to the completion of the cycle of rotation of said rotatable structure and to move the receptacle gate into closed position after the emptied receptacle has been loaded with another case of bottled beverage, means for automatically stopping the rotation of said rotatable structure after each receptacle has discharged the case therein to permit re-loading of same, means for automatically loading the empty receptacle while the rotatable structure is in stationary position, and a power-driven mechanism for rotating said rotatable structure.

12. Beverage mixing apparatus comprising a frame, an intermittently rotatable structure supported on said frame, a plurality of receptacles carried by said rotatable structure each adapted to carry a case of bottled beverage, a stationary

gear supported on said frame, a planetary gear for and rotatable with each of said receptacles and in mesh with said stationary gear, a motor, a driven gear operatively associated with said rotatable structure, a segmental driving gear operatively associated with said motor and adapted to intermittently engage said driven gear to thereby intermittently rotate said rotatable structure, means for automatically successively discharging the cases of the mixed beverage from said receptacles, automatically operable means for loading a case of beverage into the empty receptacle while said intermittently rotatable structure is in stationary position comprising a reciprocable pusher for pushing a case of bottled beverage into the empty receptacle, resilient means for retaining said pusher in loading position, a slidably mounted rack connected to said pusher adapted to be operatively engaged by said segmental gear to move said pusher and the case engaged thereby into loading position against the pressure of said resilient retaining means whereby the case of beverage is moved into the empty receptacle, said resilient means retracting said pusher into loading position upon the disengagement of said segmental gear from said rack, and a cam operated by said motor for moving said rack out of operative engagement by said segmental gear prior to the engagement of said driven gear by said segmental gear.

13. Beverage mixing apparatus comprising a frame, an intermittently rotatable structure supported on said frame, said intermittently rotatable structure comprising a rotatable drum-like body having a pair of laterally spaced end members and means rigidly interconnecting said end members, a plurality of receptacles carried by said rotatable structure each adapted to carry a case of bottled beverage, a stationary gear supported on said frame, a planetary gear for and rotatable with each of said receptacles and in mesh with said stationary gear, a pair of trunnions for each receptacle rotatably supported on said drum-like body end members, one trunnion of each receptacle being rigidly connected to one of said planetary gears, a motor, a driven gear operatively associated with said rotatable structure, a segmental driving gear operatively associated with said motor and adapted to intermittently engage said driven gear to thereby intermittently rotate said rotatable structure, means for automatically successively discharging the cases of the mixed beverage from said receptacles, and automatically operable means for loading a case of beverage into the empty receptacle while said intermittently rotatable structure is in stationary position.

14. Beverage mixing apparatus comprising a frame, an intermittently rotatable structure supported on said frame, a plurality of receptacles carried by said rotatable structure each adapted to carry a case of bottled beverage, a stationary gear supported on said frame, a planetary gear for and rotatable with each of said receptacles and in mesh with said stationary gear, a motor, a driven gear operatively associated with said rotatable structure, a segmental driving gear operatively associated with said motor and adapted to intermittently engage said driven gear to thereby intermittently rotate said rotatable structure, means for automatically successively discharging the cases of the mixed beverage from said receptacles comprising a gate for each receptacle, releasable means for retaining each of said gates in closed position to retain the case

therein, a pair of rollers carried by each gate, a gate-opening cam for each receptacle, a gate-closing cam for each receptacle, said cams being mounted on said rotatable structure and adapted to be successively alternately engaged, one by one of said pair of rollers and the other by the other one of said pair of rollers whereby the receptacle gate is opened to permit the discharge of the case of bottled beverage from the receptacle prior to the completion of its cycle of ro-

5 tation and whereby said gate is movable into closed position after the emptied receptacle has been loaded with another case of bottled beverage and as the receptacle begins another cycle of rotation, and automatically operable means for loading a case of beverage into the empty receptacle while said intermittently rotatable structure is in stationary position.
